UNITED STATES PATENT OFFICE.

RAY G. COATES, OF PASADENA, CALIFORNIA, ASSIGNOR TO VALLEY MOULD AND IRON CORPORATION, OF SHARPSVILLE, PENNSYLVANIA, A CORPORATION OF NEW YORK.

METHOD AND APPARATUS FOR CASTING INGOTS.

Application filed August 17, 1923. Serial No. 657,855.

To all whom it may concern:

Be it known that I, RAY G. COATES, a citizen of the United States, residing at Pasadena, in the county of Los Angeles, State of California, have invented certain new and useful Improvements in Methods and Apparatus for Casting Ingots, of which the following is a specification.

The present invention relates to metallurgy, and more particularly to a method and apparatus for casting top poured steel ingots.

Heretofore in the art it has been customary to cast top poured ingots one at a time. There have been methods proposed where several such molds may be simultaneously filled from the same ladle, but such prior art methods required the mechanical division of the main stream of molten metal from the ladle into streams of smaller cross-section, which would be run a relatively short time. Under these conditions only a relatively few number of molds may be simultaneously poured.

In the modern production of steel, the charges are usually poured into ladles which will hold from fifty to one hundred tons of molten steel. The length of time of pouring from the ladle is controlled by the period that the steel in the ladle will remain molten, and, therefore, it must in any case be discharged before it freezes in the ladle. Where a number of ingot molds are set up for casting, as is common in the art, it is customary to move the ladle from one mold to another or to move the molds past the pouring station by means of a train of cars on which the molds are carried. Since the time for discharging the ladle is fixed, and since the molds must be filled either individually or in small groups, the ingots last cast will be cast from colder metal than those first cast, and the time of casting per individual ingot is short as compared to the total time of ladle discharge; that is, when the first mold is filled, the filling operation as to that mold is completed, and the first ingot has commenced to solidify before the last ingot cast from the charge has been poured.

It has been recognized that top poured molds which are slowly filled produce ingots that are dense and sound. If the pouring is sufficiently slow relatively to chilling of the molten metal in the mold, the steel will

freeze from the bottom upwardly, and a shallow pool of molten metal may be carried above the freezing steel. On the other hand, where the steel is poured rapidly, the high velocity of the incoming steel causes a forced circulation which delays bottom freezing, and the mold is filled so quickly that freezing occurs over the sides and bottom simultaneously. Under these conditions, contractual cavities form, and pipes occur. It will be observed that the desirable procedure is to very slowly pour top poured ingots, but heretofore this has not been practical, since such a procedure would have increased the time period for the total pouring beyond the time when the metal in the ladle would freeze, and beyond the time allowed for other operations in the cycle of steel production.

The present invention overcomes the difficulties of the known art by providing a method and apparatus by means of which a large number of molds may each be simultaneously fed by small streams over a long period of time, and without delaying or increasing the period of ladle discharge. The filling operation occurs substantially simultaneously for each mold, and the time factor for filling each mold may be equal to that which would be required to fill a series of such molds of the same number if they were individually filled in series by old methods. Heretofore, in attempts to divide the white hot stream of metal in cross-section, it has been very difficult to maintain the size of the stream of such cross-section as to secure the best results.

In the present method a constant stream of metal is allowed to run from the nozzle of the ladle, and this entire stream is delivered intermittently to each of a series of conductors leading to the various moulds, the conductors acting more or less as intermediate receivers which deliver a constant, though variable, flow into the molds themselves. Thus, instead of attempting to divide the stream of metal cross-sectionally, the flow has in one sense been divided longitudinally. Since the longitudinal dimension of the flow is very great as compared with its cross-sectional dimension, the division of the flow into a series of parts is relatively easy.

According to the present invention, the molds may be set in a circle on bottom plates

or stools, which are the equivalents of those now used in top casting. One bottom plate may be used for each mold, or several molds may be set on one bottom plate, or, in an 5 extreme case, all of the molds may be set on one bottom plate. The molds may be of the usual kind, open at the top and bottom, and have the usual draught to facilitate "stripping". This means that in the 10 present invention the molds themselves require no especial form except that they be so designed as to allow the upper surface of the fluid metal to be one assumed under the action of gravity, and that the entering 15 stream of metal shall disturb the pool of fluid steel as little as possible.

An endless trough lined with a suitable refractory mixture is provided over the top of these molds. This refractory lining is 20 so molded as to divide this trough into a number of parts or receivers, the result being accomplished by increasing the thickness of the refractory material where such divisions are desired, yet the finished height 25 of the division is less than the full inner depth of the trough in order that the trough may act as a whole above the upper limit of the divisions. A receiver is provided for each mold, and is so formed that it will 30 drain to one point and at this point an orifice is made large enough to keep open against freezing so long as fluid metal is supplied to the receiver. This orifice discharges fluid metal smoothly into the mold. 35 Concentric with this ring of receivers is a rotary member which turns around a vertical axis. On this rotary member is arranged a "distributor" in a radial position, the central end of which is formed into a 40 "fountain", while the other end reaches to the central line of the circle of receivers. The outer end of this distributor is turned backwards from the direction of its motion. A gear, or its equivalent, is attached to the 45 distributor with connections to a suitable motive power so that it may be continuously rotated during the time of pouring the steel from the ladle. The distributor may be an open trough, or it may comprise a 50 closed runner between the fountain and the outer end if, for any reason, this becomes desirable.

The ring of receivers and the distributor with its rotating central axis and the support 55 of the latter, together with the motor and connections to drive the distributor, form an integral structure that can be placed over the molds either by an over-head crane, or by being moved out by some other means, 60 as for instance, by a car system on a suitable track. The molds themselves may be on cars and either the run under the above structure or the latter may be moved over the cars in any approved manner.

15 The principal object of the present in-

vention is the method and apparatus for casting ingots whereby a continuous stream of molten steel is passed in regular sequence over and into a series of non-chilling receivers, each of which discharges into an 70 individual mold.

Another object of this invention is the method and apparatus for casting steel ingots by passing the discharge stream from a suitable source over mold feeding receivers in such manner as to maintain superimposed layers of fresh steel in the receivers until the molds are filled. 75

A still further object of the present invention is the method and apparatus for 80 casting steel ingots which comprises subdividing the main feeder stream of molten steel into longitudinal sections and then drawing out the subdivided sections into individual streams adapted to slowly feed 85 individual molds.

Another object of the present invention is a method and apparatus for casting steel ingots by slowly pouring a plurality of ingots from a ladle charge of molten steel fed 90 to form super-imposed layers of fresh steel to receivers for feeding individual molds, whereby the pouring time of each ingot is slightly longer than the discharge period for the ladle. 95

A still further object of the present invention is the method and apparatus for slow pouring of top poured ingots comprising a series of molds arranged in a circle to be fed simultaneously from a single source, 100 supplying a movable distributor in such manner that the stream of molten steel from the distributor is successively discharged into a circular series of feeders, one for each individual mold, whereby each mold receives 105 a portion of the source stream during the entire flow of such stream.

Other and further objects of this invention will in part be obvious and will in part 110 be pointed out hereinafter by reference to the accompanying drawings forming a part of this specification.

It is realized that the present invention may be carried out in other ways and by other mechanisms without departing from 115 the scope of the invention, and, therefore, it is desired that the present disclosure shall be understood as illustrative and not in the limiting sense.

Referring now to the drawings, through- 120 out which like parts are represented by like characters.

Figure 1 is an elevational view of a more or less diagrammatic illustration of one form of apparatus embodying and for carrying out the present invention; 125

Figure 2 is a plan view of the device shown in Figure 1;

Figure 3 is a section through a portion 130 of the distributor;

Figure 4 is a detail view through a portion of a receiver and mold;

Figures 5, 6, and 7, illustrate variations in mold set ups according to the present 5 invention.

The embodiment of the invention as shown in Figures 1 to 4 inclusive comprises a series of ingot molds 1 arranged in a circle upon a casting floor 2, as an endless series. 10 These molds are set between track rails 4, which may be arranged either as a floor, or an over-head track, and which support a carriage 5. This carriage carries a trough-member 6, which comprises a supporting 15 shell 7, in which is mounted a refractory lining 8 that is divided into receivers or pockets 9 by division walls 10. These division walls 10 are not as high as the side walls of the trough formed by the refractory lining 8 so that molten metal may fill the trough over the said division walls 10. 20 The lowest portion of each receiver is provided with a discharge opening 11 arranged to be directly over an ingot mold 1 so that 25 there are as many receivers as there are molds to be filled.

A spider frame 12 extends toward the center of the circular trough 6 and carries a supporting bearing 14 in which is mounted 30 a vertical shaft 15 that carries a distributor 16 which is also formed of an open trough-like shell that is lined with refractory material. This trough preferably terminates at the inner end in a fountain basin 35 17 that is directly over the shaft 15, and at the outer end is a curved end 18 which extends directly over the trough 6 and is adapted to discharge molten metal from the distributor into the receiving trough 6. 40 The distributor is counter-weighted as at 19 to balance the weight of the distributor and contents when the device is in operation.

The lower end of the shaft 15 carries a 45 gear 20 that meshes with a pinion 21 on a power shaft 22 that may be driven by an electric motor 24. This motor 24 is adapted to be controlled by an operator on the control platform 25. The car 5 may be moved 50 by suitable clutch controlled connections with the motor 24 or by any other means suitable for the purpose, to position the receiver trough over the mold set-up.

Figures 5, 6, and 7 show the receiver 55 trough provided with trough arms 26 which are adapted to lead the molten metal from the circular receiver trough into molds set in straight rows or in rectangular groups.

During the operation of casting the above 60 described receiver trough and distributor remains over the molds and each receiver discharges into a particular mold. It will be noted that if the distributor is rotated in the direction indicated by the arrow A that its inner "fountain" end will remain in the

same place while its outer end will sweep over the entire line of receivers once in each revolution. If now a ladle 27 of molten steel is brought by an overhead crane, in the usual way, to a position such that the nozzle of the ladle is central with the fountain of the distributor and this latter is set in rotation at the desired rate, then any steel discharged by the nozzle into the fountain will be delivered by the distributor into the 70 receivers as the former sweeps over them. The entire ladle can be thus discharged into molds without moving the ladle itself provided there are molds enough to hold the contents of the ladle. If the divisions which 75 separate the receivers from each other are so placed that they intercept equal portions of the circumference described by the outer end of the distributor then the amount of metal falling into each receiver will be the 80 same.

It will be evident that if the end of the distributor discharges the fluid steel in a direction tangential to its path of revolution at the point of discharge and that if the 90 rate of rotation is such that this point of discharge has a velocity equal to the spouting velocity of the steel as it falls from the distributor then the steel itself will fall into the receivers without either radial or tangential velocity and any tendency to splash and scatter the metal will be eliminated while the metal will be well mixed. It will also be evident that the spouting velocity 95 of the metal may be largely controlled by the grade or incline given to the distributor between the fountain and its outer end. This fact, together with the consideration of the centrifugal force developed in the metal 100 due to the speed of rotation, will enable 105 practical conditions to be met.

The intermittent additions of metal to each receiver should be rapid enough to keep the contents of the receivers fluid during the operation of pouring. The sketches show the distributor as a single conductor with a mechanical counterbalance. This counterbalance may be simply another distributor receiving from the same fountain 110 and discharging also into the receivers. Any 115 irregularities in discharge between the distributors would have no ill effects because all distributors would discharge into all receivers.

The discharge orifice in the receivers 120 should be under a very low average ferrostatic head so that a small actual increase in the head due to the charge delivered by the distributor will cause a large proportionate increase in head and a consequent 125 rapid increase in flow through the orifice, as well as a rapid decrease as the head runs down so that the flow of metal into the mold itself will not be broken.

It will be noted that small variations in 130

the size of the orifices of the various receivers will cause no change in the amount of the metal received by the molds, because such small variations in the size of the 5 orifices simply cause more or less change in the head of metal over the orifice until the discharge has increased or decreased enough to counteract the variations.

By the above means the entire stream of

- 10 metal flowing from a ladle may be evenly discharged into a large number of molds. If it is desired to discharge more metal into one mold than into others it is only necessary to arrange the position of the divisions 15 so as to intercept the required proportion of the path of the discharging end of the distributor.

In order to establish a pool of steel in the mold it is desirable to have a strong feed 20 when the pouring is first started into the mold. It may be accomplished by employing a rather large nozzle for the ladle with the nozzle at first wide open and after the first few revolutions of the distributor, closing 25 down the stopper to such a point as will use the desired time in the pouring.

Having thus described my invention, what I claim is:

1. The method of simultaneously pouring 30 a plurality of ingot molds, which method comprises providing a plurality of receivers having discharge openings leading to ingot molds, with the discharge openings of such size as to pass a volume of molten metal 35 which is less than the volume of the main supply stream; and intermittently feeding the receivers from the main stream with sufficient rapidity and volume to maintain a supply of molten metal in each receiver 40 until its respective mold is properly filled.
2. The method of simultaneously pouring a plurality of ingot molds, which method comprises providing a plurality of connected receivers, each having a discharge opening 45 leading to an ingot mold, with the discharge opening of such size as to pass a volume of molten metal which is less than the volume of the main supply stream; and intermittently feeding the receivers from the 50 main stream by a distributor movable over the receivers with sufficient rapidity so as to maintain a supply of molten metal in each receiver until its respective mold is properly filled.
- 55 3. The method of simultaneously pouring a plurality of ingot molds, which method comprises providing a plurality of receivers having discharge openings leading to ingot molds; and intermittently feeding the receivers from the main stream.
4. The method of simultaneously pouring 60 a plurality of ingot molds, which method comprises arranging a plurality of receivers in an endless series, with each receiver adapted to feed an ingot mold; and dis-

charging a main supply stream into the receivers to maintain a fresh supply of molten metal in said receivers until the molds are filled.

5. The method of simultaneously pouring 70 a plurality of ingot molds, which method comprises arranging a plurality of receivers in an endless series, with each receiver adapted to feed an ingot mold; and discharging a movable main supply stream 75 into the receivers at a sufficient rate to maintain a fresh supply of mixed molten metal in said receivers until the molds are filled.

6. The method of simultaneously pouring 80 a plurality of ingot molds, which method comprises arranging a plurality of ingot molds in an endless series, and discharging a main supply stream intermittently into each of said molds.

7. The method of simultaneously pouring 85 a plurality of ingot molds, which method comprises dividing a main supply stream of molten steel transversely into a plurality of sections; superimposing later sections of 90 said stream over earlier sections thereof, and feeding said superimposed sections to individual ingot molds.

8. The method of simultaneously pouring 95 a plurality of ingot molds, which method comprises dividing a main supply stream of molten steel transversely into a plurality of sections; superimposing later sections of 100 said stream over earlier sections thereof to cause a mixing of the metal thereof, and feeding said superimposed sections of the main stream to individual ingot molds over a period of time substantially equal to the discharge period for the main stream.

9. The method of simultaneously pouring 105 a plurality of ingot molds, which method comprises moving the discharge end of a main supply stream and dividing a main supply stream of molten steel transversely while moving into a plurality of sections; superimposing later sections of 110 said stream over earlier sections thereof, and slowly feeding said superimposed sections to individual ingot molds.

10. The method of top pouring a plurality 115 of ingot molds, which method comprises repeatedly passing a continuous stream of molten metal in regular sequence over and into an endless series of receivers, each of which latter discharges into a particular mold.

11. The method of top pouring a plurality 120 of ingot molds, which method comprises repeatedly passing a continuous stream of molten metal in regular sequence over and into an endless series of receivers, each of which latter discharges into a particular mold, the time of discharge from the receivers being substantially equal to the total time of discharge of the continuous stream.

12. The method of top pouring a plurality 125

of ingot molds, which method comprises repeatedly passing a continuous stream of molten metal in regular sequence over and into an endless series of ingot molds.

5 13. The method of top pouring a plurality of ingot molds, which method comprises moving a stream of molten steel over a supply station for each individual mold to feed each mold from successive portions 10 of the molten stream during the entire period required to fill all of the said plurality of molds.

14. The method of top pouring a plurality of ingot molds, which method comprises 15 intermittently moving a main stream of molten steel over a supply station for each individual mold to feed each mold from successive portions of the main molten stream during the entire period required to fill all 20 of the said plurality of molds.

15. The method of top pouring a plurality of ingot molds, which method comprises moving a stream of molten steel over a supply station for each individual mold to 25 feed each mold from successive portions of the molten stream; and controlling the size of the streams to the individual molds to cause the filling period for each mold to continue during the entire period required 30 to fill all of the said plurality of molds.

16. The method of simultaneously pouring a plurality of ingot molds by providing an endless series of receivers, each connected to an ingot mold, and discharging a movable main supply stream into the receivers with the rate of movement being substantially equal to the rate of flow of the molten metal in the said main stream.

40 17. The method of simultaneously pouring a plurality of ingot molds by providing an endless series of receivers arranged in the form of a circle, with each receiver connected to an ingot mold; and discharging a movable main supply stream into the receivers with the rate of movement of the discharge end of the main stream being substantially equal to the rate of flow of the molten metal in the said main stream at the discharge end thereof.

45 50 18. The method of slow pouring top poured ingot molds, which method comprises dividing the main supply stream transversely into a plurality of sections and controlling the flow of the sectionalized portions to individual ingot molds so that the period of flow from the sectionalized portions to the molds is slightly greater than the total period of flow of the main supply stream.

60 65 19. The method of slow pouring top poured ingot molds, which method comprises dividing the main supply stream transversely into a plurality of sections; superimposing later sections over earlier sections; and controlling the flow of the

superimposed sectionalized portions to individual ingot molds so that the period of flow from the sectionalized portions to the molds is slightly greater than the total period of flow of the main supply stream. 70

20. The method of top pouring a steel ingot, which comprises slowly pouring a small stream of molten steel from a shallow pool directly into a vertical mold; intermittently replenishing the shallow pool with 75 fresh hot steel during the pouring of an ingot; and rapidly chilling the accumulated metal in the mold to maintain a shallow layer of molten steel over the rapidly freezing lower metal. 80

21. The method of top pouring a steel ingot, which comprises pouring a continuous small stream into substantially the center of a vertical ingot mold, and preventing the freezing of the stream by intermittently adding fresh hot steel during the pouring 85 of an ingot to the source of supply for said stream.

22. The method of discharging a ladle of molten steel and simultaneously casting a plurality of ingots from the ladle charge, comprising intermittently leading the ladle stream to the separate sources of a plurality of small independent mold feeding streams so that each mold feeding stream receives 90 a portion of the first and also a portion of the last of the ladle charge. 95

23. The method of discharging a ladle of molten steel and simultaneously casting a plurality of ingots from the ladle charge, comprising a continuous ladle stream intermittently leading the ladle stream to each of a plurality of shallow pools comprising 100 the sources of a plurality of small mold feeding streams so that each mold feeding stream receives a portion of the first and also a portion of the last of the ladle charge. 105

24. A device of the class described comprising a receiver for molten metal, said receiver being provided with discharge means leading to an ingot mold, and a supply member movable over said receiver to intermittently supply said receiver with molten metal during the pouring of an ingot 110 in said mold. 115

25. A device of the class described comprising a circular receiver for molten metal, said receiver being provided with discharge means leading to an ingot mold, and a swinging supply member having one end movable over said receiver to intermittently supply said receiver with molten metal, the other end of said member being located substantially at the center of the circular receiver. 120 125

26. A device of the class described comprising in combination a trough divided into a plurality of independent receivers, each adapted to discharge into an ingot mold, a supply member adapted to travel 130

over said trough to supply molten metal to the receivers in said trough, and means to move said member.

27. A device of the class described comprising in combination a supporting frame, a trough mounted upon said supporting frame and divided into a plurality of receivers, each adapted to discharge into an ingot mold, a supply member adapted to travel over said trough to supply molten metal to said trough, and means to move said member at a rate of travel equal to the flow of metal from said supply member.

28. A device of the class described comprising in combination a carriage, a receiver trough mounted on said carriage, conduits from said receiver trough leading to ingot molds, and a swinging supply member having a discharge end movable over said trough to distribute molten metal lengthwise of said trough, the other end of said member being provided with a fountain basin adapted to be located to receive a ladle stream.

29. A device of the class described comprising in combination a carriage, a supply member adapted to move over a plurality of ingot molds and supply molten metal thereto, and means to move repeatedly said supply member over said molds while said carriage is stationary.

30. A device of the class described comprising in combination a receiver trough, a plurality of receivers in said trough with the divisions between said receivers being of less height than the sides of said trough, each receiver being adapted to feed an ingot mold, and means to supply molten metal to the receivers in said trough.

31. A device of the class described comprising in combination a curved receiver trough, a swing supply arm adapted to move over said trough, and means to move said supply arm.

32. A device of the class described comprising in combination a circular trough, conduits from said trough leading to ingot molds, and means to supply molten steel to said circular trough.

33. In the art of casting ingots, the combination of a plurality of ingot molds, a common trough member to lead molten metal to said molds and distributing means

constantly moving over said trough to supply molten metal to different portions of 55 said trough at different times.

34. In the art of casting ingots, the combination of a plurality of ingot molds, a common trough member to lead molten metal to said molds, a supply member movable lengthwise of said trough and being adapted to supply molten metal to said trough, and means to move the discharge end of said supply member at the same rate of speed as the flow of the molten metal 65 from said supply member.

35. The method of simultaneously pouring a plurality of ingot molds, which method comprises arranging a plurality of receivers in an endless series, with each receiver 70 adapted to feed an ingot mold, and discharging a main supply stream from a moving distributor into the receivers at a sufficient rate to maintain a fresh supply of mixed molten metal in said receivers until 75 the molds are filled.

36. The method of top pouring a plurality of ingot molds, which method comprises repeatedly passing a continuous stream of molten metal in regular sequence 80 over and into a series of ingot molds during the pouring of an ingot in each of said molds.

37. The method of top pouring a plurality of ingot molds, which method comprises repeatedly passing a continuous stream of molten metal in regular sequence over and into a series of receivers, each of which receivers discharges into a particular mold.

38. The method of top pouring a steel 90 ingot which comprises slowly pouring a small stream of molten metal from a receiver into a vertical mold, and intermittently replenishing the supply of steel in said receiver with fresh hot steel while said 95 ingot is being poured.

39. A device of the class described comprising in combination a carriage, a receiver trough mounted on said carriage, a plurality of receivers in said trough, said receivers having conduits leading to ingot molds, and a supply member movable lengthwise of said trough to distribute molten metal to said receivers.

RAY G. COATES.
